C. P. CUNNINGHAM.
EXTENSION TABLE.
APPLICATION FILED MAY 21, 1915.

1,191,159.

Patented July 18, 1916.

UNITED STATES PATENT OFFICE.

CHARLES P. CUNNINGHAM, OF LOUISVILLE, KENTUCKY.

EXTENSION-TABLE.

1,191,159.

Specification of Letters Patent.

Patented July 18, 1916.

Application filed May 21, 1915. Serial No. 29,511.

To all whom it may concern:

Be it known that I, CHARLES P. CUNNINGHAM, a citizen of the United States, and a resident of Louisville, in the county of Jefferson and State of Kentucky, have invented an Improvement in Extension-Tables, of which the following is a specification.

This invention relates to tables, and more particularly to a novel extension device therefor.

One of the objects of the present invention is to provide an extension device designed to facilitate the adjustment of the table to different sizes and prevent warping of the parts, which sometimes occurs in ordinary constructions.

Another object is the provision of a device of this character comprising a bridge piece and slides movable relative thereto and so constructed as to be readily detached therefrom.

A still further object is to provide an extension device of simple construction, durable, effective in carrying out the purpose for which it is designed and one which may be manufactured at a minimum cost.

The inventive idea involved is capable of receiving a variety of mechanical expressions, one of which, for the purpose of illustrating the invention, is shown in the accompanying drawing, in which—

Figure 1 is a perspective view of a table of pedestal type showing the invention applied thereto. Fig. 2 is a fragmentary view 35 of the bridge bar of the table and the extension device, the same being shown in perspective. Figs. 3, 4 and 5 are detailed perspective views of the different parts of the extension device. Fig. 6 is a section on the 40 line 6—6 of Fig. 2. Fig. 7 is a transverse section on the line 7—7 of Fig. 6, and Fig. 8 is an enlarged fragmentary side elevation of the bridge piece showing the manner in which one of the slides is connected thereto.

45 Referring more particularly to the accompanying drawing, in which like reference characters indicate similar parts, the numeral 10 indicates generally a table having a pedestal 11 with the bridge bar 12 at the top thereof.

50 The extension device which comprises the essential feature of this invention, is preferably made of sheet metal and includes a pair of bridge pieces 13 secured to and extending transversely of the bar 12 adjacent the ends thereof. Each of the bridge pieces 13 com-

prises an inverted U-shaped body portion 14 having the base flanges 15 extending laterally from the longitudinal edges thereof. These base flanges are provided with 60 spaced openings 16 for the reception of suitable fastening devices whereby the piece is secured to the bar 12. Each side of the body portion 14 is provided with an elongated slot 17, opposite ends of each slot being provided with an enlarged opening 18 for a purpose which will appear in the course of this description. The material from which the slot 17 is formed is folded back, as 65 shown, to reinforce the structure.

70 A slide member generally indicated by the numeral 19 is arranged on each side of the body portion 14 of the bridge piece and is provided with a lateral flange 20 extending outwardly therefrom and arranged in 75 overhanging relation to the base flange 15 which extends from the side of the body portion 14 to which said slide is connected. The flange 20 is provided with suitable openings 21 for receiving fasteners whereby the 80 same is connected to the under-side of the top of the table. In order to guide the slide member 19 in its movements relative to the bridge piece, the former is provided with oppositely disposed lugs 22 struck from the 85 side adjacent one end thereof and adapted to engage the slot 17. There is also provided further means for retaining the slide 90 member 19 in engagement with the body portion 14 which consists of a projection 23 in the 95 form of an ear struck out of the side of the body portion 14 and having its extremity 24 bent inwardly and downwardly so as to engage an elongated flange 25 formed upon the bottom edge of the slide member 19. The sides of each of the members 19 are also provided with small protuberances 26 which are adapted to engage the adjacent faces of the body portion 14 to space the parts and 100 reduce friction therebetween.

105 In assembling the device, each of the slide members 19 is placed in the position shown in Fig. 8 at right angles to the bridge piece and has the lugs 22 inserted into the opening 18. The said lugs 22 are of such a width as to permit of the insertion thereof into the slot 17 and thereby permit the movement of the slide to the position shown when the same will overlap the periphery of the opening 18, after which the slide member is 110 swung to a horizontal position so that the projection 23 formed in the opposite end of

the bridge piece may be engaged with flange 25 of said member. In order to permit of this turning movement, the adjacent end of the base flange 15 is cut away as indicated 5 at 27 and the adjacent end of the slide member is rounded as indicated at 28 thus permitting of the free turning movement of the latter member. From the foregoing description it will be apparent that each of 10 the slide members has a longitudinal movement relative to the bridge piece in either direction, thus permitting of the opening and closing of the top of the table in order to vary the size thereof.

15 I claim:—

1. An extension device comprising a bridge piece consisting of a substantially U-shaped body portion having lateral base flanges projecting from the longitudinal edges thereof, said body portion being provided in the sides thereof with opposed slots and enlarged openings communicating with one end of each slot, and a slide arranged on each side of said body portion and provided with guide lugs adapted to engage the slot in the adjacent side of said bridge piece, said lugs having a pivotal movement in the opening in said slot.

2. An extension device comprising a bridge piece consisting of a substantially U-shaped body portion having lateral base flanges projecting from the longitudinal edges thereof, said body portion being provided in the sides thereof with opposed slots and enlarged openings communicating with one end of each slot, a slide arranged on each side of said body portion and provided with guide lugs adapted to engage the slot in the adjacent side of said bridge piece, 35 said lugs having a pivotal movement in the opening in said slot, and a projection on

each side of the body portion of said bridge piece adapted for engagement with the adjacent slide for guiding the same.

3. An extension device comprising a 45 bridge piece consisting of a substantially U-shaped body portion having lateral base flanges projecting from the longitudinal edges thereof, said body portion being provided in the sides thereof with opposed slots 50 and enlarged openings communicating with one end of each slot, a slide arranged on each side of said body portion and provided with guide lugs adapted to engage the slot in the adjacent side of said bridge piece, 55 said lugs having a pivotal movement in the opening in said slot, a projection on each side of the body portion of said bridge piece adapted for engagement with the adjacent slide for guiding the same, and protuberances in the sides of said slides for spacing the same from said bridge piece.

4. An extension device for tables comprising a bridge piece having a slot terminating at one end in an enlarged opening, 65 and a slide coöperating with said bridge piece and having means engaging said slot to guide said slide, said means having a pivotal movement in the enlarged end of said slot whereby said slide may be attached 70 to and detached from said bridge piece.

5. An extension device for tables comprising a bridge piece having a guide slot therein and having a projection formed thereon, and bent to provide a guide groove, 75 a slide member coöperating with said bridge piece and having a flange upon one edge thereof adapted for engagement with the guide groove formed by said projection, and means engaging said guide slot for guiding 80 said slide.

CHARLES P. CUNNINGHAM.
